ATTORNEY

UNITED STATES PATENT OFFICE.

GEORGE F. WHITNEY, OF NEW YORK, N. Y., ASSIGNOR TO UNITED STATES SUGAR CANE HARVESTER CORPORATION, OF NEW YORK, N. Y., A CORPORATION OF DELAWARE.

CANE-CUTTING MACHINE.

Application filed April 14, 1920, Serial No. 373,685. Renewed April 29, 1924.

To all whom it may concern:

Be it known that I, GEORGE F. WHITNEY, a citizen of the United States, residing in the city of New York, in the county of New York and State of New York, have invented certain new and useful Improvements in Cane-Cutting Machines, of which the following is a specification.

My invention relates to a machine for cutting cane, particularly sugar cane, in the field.

Several forms of machine have been heretofore proposed for cutting sugar cane, but so far as I am aware none have proven successful and it is still the general practice to cut the cane manually by means of the "machete". At best, manual cutting is slow and expensive and the principal object of my invention is to provide a simply constructed machine, operating on what I believe to be a new principle in this kind of mechanism, for cutting sugar cane when standing in the field.

The preferred form of the invention is illustrated in the accompanying drawing, in which Fig. 1 is a plan view of the machine; Fig. 2 is a sectional view on the line 2-2 of Fig. 1; and Fig. 3 is a similar view on the line 3-3 of Fig. 1.

In carrying my invention into practice, I employ a saw for severing the cane, and it has been demonstrated in practice that by sawing the cane a clean through severance is secured fully equivalent to the machete cut, but effected in much less time and obviously at considerably lower cost.

Referring to the drawing, 10 denotes the body of a self propelled vehicle of any suitable type, carrying the sawing mechanism. Secured to a shaft A at one side of the body 10 is a pair of brackets 11, 12, which pivotally support at 13 a substantially triangular frame comprising the bars 14 and 15 and the connecting cross-brace 16. As shown more particularly in Fig. 3, the bar 15 is provided with a head 17 which is substantially T-shaped in cross section. The head 17 is designed to support the saw proper, which is reciprocated on such head.

Embracing the head 17 is a housing comprising a rear recessed wall 18 and the housing section formed of the front wall 19 and the top and bottom walls 20 and 21, the latter being secured to the rear wall 18 by bolts 22 or equivalent fastening means. One

of the walls, for example the wall 21, is extended to form a flange 23 designed to project parallel or substantially parallel to the ground when the machine is in operative position. The connection between the wall 19 and the flange 23 is strengthened by the webs 24 arranged at intervals.

The flange 23 is designed to have attached thereto the saws 25, such attachment being effected by any suitable means, such as bolts 26. It will be noted that I prefer to use a plurality of saw sections 25 in lieu of a single long saw blade, and that each section is removably attached to the supporting flange 23, so that in case of need any section 25 may be removed and attached independently of the other sections. As indicated in Fig. 1, the saws are preferably provided with lance teeth which cut with equal facility in either direction of reciprocation.

One end of the wall 19 is provided with a projecting arm 27 to which is pivotally connected one end of a pitman 28 the other end of which is pivotally secured to the cranks 29 bearing in the walls 30. The latter extend outwardly from a sleeve 31 fast on the shaft A. The cranks are driven by any suitable mechanism, that shown in the drawing comprising a sprocket wheel 32 on one of the crank arms over which a sprocket chain 33 travels. Carried below the bed of the vehicle body 10 is a counter shaft 34 rotated by the sprocket chain 33 from the motor 36, and near one end of the shaft 34 is a sprocket wheel 37 over which the chain 33 passes. Obviously, as the shaft 34 is rotated from the motor 36 the cranks 29 will impart reciprocating motion to the housing carrying the saw members 25.

In order that the sawing mechanism may be raised and lowered as desired, I provide the following instrumentalities:—pivoted to the outer end of the housing 19 is one end of a breakable link consisting of the parts 38 and 39 connected by the pivot 40. The other end of the breakable link is connected to a spur gear wheel 41 rotatably mounted at the upper end of a standard 42 which rises from the vehicle body 10. Meshing with the gear wheel 41 is a pinion 43 fast on a shaft 44 carrying a crank handle 45, the shaft 44 bearing in the standard 42. It will be apparent that by turning the handle 45 in the proper direction the link 38-39 will be operated to raise or lower the saw-

ing mechanism, and in this action the frame 14—15—16 which carries the latter will turn about the pivots 13.

I preferably provide a guard 46 near the 5 forward part of the vehicle to prevent the entrance of obstructive matter into the gearing and like parts carried at the side of the body 10.

The operation of the machine has been 10 generally indicated in the foregoing description and may be briefly summarized as follows:—To place the machine out of operation, the handle 45 is turned in the proper direction, causing the link 38—39 to 15 break at the pivot 40 thus raising the sawing mechanism into a substantially vertical position. If the machine is to be operated, the handle 45 is reversely turned, lowering the sawing mechanism into a substantially horizontal 20 position whereupon the motor 36 is started thus causing the saws 25 to reciprocate through the connections above described. The vehicle is advanced parallel to the rows of cane to be cut, and as it advances it cuts the cane, the stalks falling in a direction away from the machine. Should 25 a tree stump or other obstruction be encountered the sawing mechanism may be quickly raised and when the obstruction is passed 30 the sawing mechanism may be as quickly lowered to continue its operation.

I claim:—

1. A cane cutting machine comprising a vehicle, a frame projecting therefrom and 35 provided with a T shaped guide, a saw frame reciprocally mounted on said guide, and means for reciprocating said saw frame.

2. A cane cutting machine comprising a

vehicle, a frame projecting therefrom and provided with a T shaped guide, a saw 40 frame reciprocally mounted on said guide, sectional saws carried by said saw frame, and means for reciprocating said saw frame.

3. A cane cutting machine comprising a vehicle, a frame pivotally mounted at one 45 side thereof, said frame being provided with a pivoted link connection adapted to support the frame at its outer end, a saw bar mounted in said frame and provided with saw sections, and means for reciprocating said saw bar.

4. A cane cutting machine comprising a vehicle, a frame movably connected to said vehicle, a housing movably supported on said frame, a saw attachable to said housing, and means for reciprocating said housing.

5. A cane cutting machine comprising a vehicle, a frame movably connected to said vehicle, said frame having one member T- 60 shaped in cross section, a housing slidable on said member, a saw attachable to said housing, and means for reciprocating said housing.

6. A cane cutting machine comprising a vehicle, a saw-carrying frame pivoted to one side of said vehicle, a standard mounted on said vehicle and provided with a pivoted link connection with the outer end of said frame, and means carried by said standard 70 to collapse said links one over the other for raising and lowering said frame.

In testimony whereof I have affixed my signature.

GEORGE F. WHITNEY.
